UNITED STATES PATENT OFFICE.

JOHN Q. SHERMAN AND ALBERT W. METZNER, OF DAYTON, OHIO; SAID METZNER
ASSIGNOR TO SAID SHERMAN.

MANIFOLDING REGISTER.

Application filed October 30, 1922. Serial No. 597,723.

Our invention relates to manifolding machines and more particularly to autographic registers, same being one type of manifolder on which the notations are made by hand writing.

It is the object of our invention to provide a simple and effective means for providing a total summary record strip in machines of the general character shown and described in the U. S. Patent to T. F. Schirmer No. 940,481.

A total summary requires only the registration of those items on a shipping bill or merchandise strip which give the totals or certain specific parts of the transactions set down on the bill or strip. Thus only a relatively small amount of space on the summary record strip needs to be moved across the writing support of manifolding machines as compared to the amount necessary to make up a complete form to be issued.

It is the object of our invention to provide for the mounting, tensioning and rewinding of a summary strip in a simple manner, so as to give a tight well formed roll and it is also our object to so construct this device that it is well adapted to production on different sizes of machines without altering the mechanism in any essential respect.

These objects and other advantages to be noted we accomplish by that certain construction and arrangement of parts to be hereinafter more specifically pointed out and claimed.

In the drawings,

Figure 1 is a detail side elevation of the essential features of our invention.

Figure 2 is a top plan view detail of the tension finger and mounting.

Figure 3 is a front and edgewise view of the ratchet pawl.

It will be noted that no attempt has been made to show a complete autographic register, and reference is made to the Schirmer patent, above identified for this purpose.

We have indicated the side frame pieces 1, the writing table or tablet 2, which as in the usual machines of the Schirmer type, is supported on the side frame pieces, and the hinged lid or top 3. In the top is the tension roller 4, housed in a housing 5, and spring-pressed downwardly by springs 6. The edge 8^a of the top forms a tear-off blade.

The paper feed for the forms to be is-

sued is formed of shaft 7, on which are pin wheels 8, said shaft being rotated counterclockwise to effect the feed.

The issued form strips are mounted in rolls 10 set on shafts 11 in the machine. The manner of mounting these shafts 11 is non-essential. The form strips are brought up over idler rolls 12, and thence over the writing table where the strips which are marginally punched are set over the pins 13 of the feed device. Carbon paper is interleaved between the form strips and the lower form and the summary strip.

On the feed shaft, exterior of the machine frame is a handle 14, which is controlled for individual complete rotations by any desired form of releasable stop 15.

All of the above features are common in autographic registers of the type noted, and in their details form no part of this invention, as any form of feeding device for issuing and marking on form strips would serve the purpose.

The total summary strip 16 is mounted in the form of a roll 17 on the shaft or spindle 18, which is rotatably supported in any desired manner in the machine frame.

Formed in the base 19 of the machine frame is a slot 20; a tension finger 21 is provided having a base plate 22, which rests on the base 19. Two tongues 23 and 24 depend from the base through the slot to guide the base 22.

One of the tongues, i. e. the tongue 23, is formed as a hook to which is attached a spring 25, which spring is attached also to a hook 26 beneath the base of the machine.

It will be noted of the machine base 19 that it is formed of a sheet metal piece curled down at the edges 27 to form an elevated base, beneath which the hook 26 will have clearance.

The construction above described is so placed that the finger 21 bears against the roll 17, in such a way as keeps the roll firmly against accidental unwinding, or looseness of the strip 16.

The strip 16 is passed up over an idler 28, and thence is drawn along the writing table for a short space sufficient to cover the summary space of lines on which the totals and data are inscribed on the issued strips. It then passes down through a slot 29 formed with a sloping rear wall 30, to the underside of the writing table again.

A spindle 30^a is mounted in the frame of the machine forwardly and beneath the feed shaft, this spindle serving to mount a roll core 31, on which is a securing bar 32; the 5 core and bar are familiar constructions in the art.

On the core is a ratchet or gear 33, which lies preferably close to the one side wall of the machine. A pawl 34, pivoted at 35 on 10 the side frame and spring pulled at 36, serves to prevent back motion of the core, and this pawl also serves to hold the ratchet on the core in proper position; thus a finger 37 on the pawl is so arranged as to straddle 15 the ratchet on the inner side thereof, and hold it in position against the side wall of the machine.

On the side wall of the machine is a support bracket piece 38 for the operating pawl 20 of the rewind core 31. This piece is formed with a tapering elevated portion 24^a between which and the side frame, slides the operating pawl 39.

The pawl is formed with a tooth 40 for 25 engaging the ratchet 33, and lies under the bracket or housing under the influence of a spring 41. This spring is secured to the tip 42 of the bracket which is like the tip 24^a, but is concealed by the spring in Figure 1 30 and to the notched pin or projection 43, at the tooth end of the pawl, so as to hold the pawl upwardly with its tooth acting as a stop against the bracket or housing, and in a substantially vertical position.

35 On the feed shaft is mounted a disk or cam 44, having a nose 45, which will engage and actuate the pawl. The bracket or housing is arranged that as the feed shaft revolves the pawl is depressed by the nose on 40 the cam, which passes the pawl during each complete rotation of the feed shaft.

As the pawl is positioned to contact with the ratchet it will engage it and its mounting will permit it to rock over as it advances 45 the ratchet.

In operation the machine is first loaded by bringing the summary strip up over its end of the writing table and down to the rewind core to which it is attached by means 50 of the securing bar. The form strips to be issued are placed with the apertures therein over the pins of the pin wheels and carbon paper is interleaved between the forms and the lower form and the summary. The 55 operator after making the desired entry and summary thereof on the topmost form strip, releases the feed handle, and revolves it once, as described, resulting in feeding out one set of forms. During the feed it will also result in the cam nose striking down the pawl, so that the pawl revolves the rewind core, the pawl being released before the operation is complete, and the handle has come up against the stop again.

60 Since the storage roll of the summary is

tight, a feed of the proper length of a taut strip will result, so far as the summary is concerned, which feed depends upon the length of the pawl and the position of the feed shaft.

70 In forming the pawls, we find that they can be made up in a single size, with a long head 39^a, which is preferably scored with lines 39^b (Figure 3), to serve as a guide. Then, dependent upon which size machine 75 is to be made up, the pawl can be cut down along the indication lines so as to give the desired amount of summary feed.

The bracket, position of the bracket, shape 80 of the shank and tooth of the pawl can remain constant, which simplifies the manufacturing operations in setting up machines from stock parts. Also a new pawl can be provided for a user if he desires a different length of summary in a machine already constructed, and in operation.

85 We contemplate also the use of special cam disks on the feed shaft to provide more than one cam nose, such as is indicated in dotted lines 45^a (Figure 1).

90 The method of mounting the tension finger for the storage roll of the summary strip is simple and easily installed, and provides a constant friction as the tip of the finger is arched so as to take a full position of contact and acts as a follower under influence of the spring. As the summary storage roll becomes smaller, the tension finger contacts with an increasingly large proportion of the total area of the roll, and it always maintains a vertical position due to the action of the spring, pulling the curved end of the finger against the face of the roll.

95 Having thus described our invention what we claim as new and desire to secure by Letters Patent, is:—

1. A device for operating the rewind roll of a summary strip in manifolding machines, comprising in combination a frame with a rotary feed shaft therein, a rotary rewind roll, a toothed member thereon, a pawl slideable as to the frame, and in the path of the toothed member, and means on the feed shaft for operating the pawl, whereby the pawl by contact with the toothed member will 1 actuate the rewind roll.

2. A device for operating the rewind roll of a summary strip in manifolding machines, comprising in combination with a rotary feed shaft, a spring-actuated pawl mounted in the machine independent of the feed shaft, an abutment on the feed shaft to engage said pawl and slide it lengthwise, a rewind roll, and a ratchet on the rewind roll in the path of the pawl and adapted to be 1 actuated thereby.

3. A device for operating the rewind roll of a summary strip in manifolding machines, comprising in combination with a rotary feed shaft, a spring-actuated pawl mounted 1

in the machine independent of the feed shaft, an abutment on the feed shaft to engage said pawl and slide it lengthwise, a rewind roll, and a ratchet on the rewind roll in the path 5 of the pawl and adapted to be actuated thereby, the mounting means of the pawl comprising a housing within which the pawl is

mounted, said housing adapted to permit the pawl to rock as well as to slide, and a spring connected to the housing and the pawl so as 10 to hold the pawl normally in line to engage the ratchet.
